BOX FOR POWDERED MATERIALS

Albert W. Hagan, Stratford, Conn., assignor to Roy S. Sanford & Company, Oxford, Conn., a partnership

Application August 21, 1956, Serial No. 42,691

Term of patent 14 years

(Cl. D58—12)

Fig. 1 is a perspective view of a box for powdered materials showing my new design;

Fig. 2 is an end elevational view thereof;

Fig. 3 is a front elevational view thereof; and

Fig. 4 is a cross-sectional view thereof taken on the line 4—4 of Fig. 3.

The rear not shown is the same as the front shown.

The broken lines shown on the drawing are intended to represent indeterminate length.

The characteristic features of my design for the box for powdered materials disclosed reside in the flattened

panel portions on the corners of the box having the configurations shown.

I claim:

The ornamental design for a box for powdered materials, substantially as shown and described.
